UNITED STATES PATENT OFFICE

107,576

DESIGN FOR A STATUETTE OR SIMILAR ARTICLE

Nelson A. Long, Duluth, Minn.

Application February 1, 1936, Serial No. 60,952

Term of patent 14 years

To all whom it may concern:

Be it known that I, Nelson A. Long, a citizen of the United States, residing at Duluth, in the county of St. Louis and State of Minnesota, have invented a new, original, and ornamental Design for a Statuette or Similar Article, of which the following is a specification, reference being had to the accompanying drawings, forming part thereof.

I claim:

The ornamental design for a statuette or similar article as shown.

NELSON A. LONG.
